Inventor:
Chas N. Tyler,

CHARLES N. TYLER, OF NEW YORK, N. Y.

Letters Patent No. 88,097, dated March 23, 1869.

IMPROVED CLOTHES-PIN.

The Schedule referred to in these Letters Patent and making part of the same.

To all whom it may concern:

Be it known that I, CHARLES N. TYLER, of New York, in the county of New York, and State of New York, have invented a new and useful Improvement in Clothes-Pins; and I do hereby declare that the following is a full and exact description thereof, reference being had to the accompanying drawings, and to the letters of reference marked thereon.

My invention consists in so bending a wire spring, in making a clothes-pin, as to make the pressure bear mainly at the centre of the clamping-rollers, and equally, or nearly so, upon their ends.

In the accompanying drawings—

Figure 1 is a view of my improved clothes-pin, showing the ends of the rollers, and the mode of fastening them by washers, soldered to the rivets.

Figure 2 shows wire bent over to the middle of the roller.

Figure 3 is a top view of the pin.

In making wire clothes-pins, provided with clamping-rollers, it is important to bring the main tension of the spring at or near the middle of the rollers, and to have the pressure equal, or nearly equal, at both ends of the rollers, in order to give the pin a strong hold upon the line and clothes, when swinging in the wind.

To accomplish this object, I bend the wire spring over the top of the rollers, as shown at A, fig. 2, there being two curves in the wire, one at the end of the roller, and the other at or near the middle.

This arrangement of the spring gives a central bear-

ing upon the rollers, with an equal or nearly equal tension at the ends.

In attempting to open the rollers at one end, the central angles of the spring must be twisted, thus giving a strong resistance, which cannot be obtained without my improvement.

The wire being very small, it is not easy to rivet the washer B in place, and if the washer turns with the roller, the rivet-head and the hole in the washer will soon wear far enough to let the washer slip off, and thus spoil the pin.

In order to prevent this difficulty, I make my improved clothes-pin with the washers soldered immovably in place upon the wire or rivet.

I am aware that rollers have been used on clothes-pins, the bearing of the wire spring being mainly at one end of such rollers; therefore I confine my improvement to the above mode of bending the wire, so as to bring the main pressure at or near the middle of the rollers.

Having thus described my invention,

What I claim, and desire to secure by Letters Patent of the United States, is—

So bending the wire spring of a clothes-pin as to produce the main tension at or near the middle of the clamping-rollers, and an equal or nearly equal pressure at the opposite ends of the rollers, substantially in the manner set forth.
